UNITED STATES PATENT OFFICE

BENJAMIN KIRSCH, OF CHICAGO, ILLINOIS, ASSIGNOR TO AUTO RADIATOR MANUFACTURING COMPANY, OF CHICAGO, ILLINOIS, A CORPORATION OF ILLINOIS

DESIGN FOR A COMBINED RADIATOR SHELL AND DEFLECTOR

Application filed May 31, 1932. Serial No. 43,942. Term of patent 7 years.

To all whom it may concern:

Be it known that I, BENJAMIN KIRSCH, a citizen of the United States, and resident of Chicago, Cook County, Illinois, have invented a new, original, and ornamental Design for a Combined Radiator Shell and Deflector, of which the following is a specification, reference being had to the accompanying drawing, forming part thereof, in which

Fig. 1 is a front elevation of a combined radiator shell and deflector, in closed position, showing my new design;

Fig. 2 is a view similar to Fig. 1 showing the deflector in open position;

Fig. 3 is a side elevation of Fig. 2; and,

Fig. 4 is a plan view of Figs. 2 and 3.

I claim:

The ornamental design for a combined radiator shell and deflector, substantially as shown.

In testimony whereof, I have signed my name to this specification this 24th day of May, 1932.

BENJAMIN KIRSCH.
